TRAILER BODY

Robert E. Rahauser, York, Pa.

Application December 13, 1954, Serial No. 33,508

Term of patent 14 years

(Cl. D14—3)

Fig. 1 is a side elevational view of a trailer body showing my new design.

Fig. 2 is a side elevational view opposite that shown in Fig. 1.

Fig. 3 is a front elevational view of said body.

Fig. 4 is a rear elevational view of said body.

The wheels, counter, and hitch member shown by means of broken lines are disclosed for illustrative purposes only.

I claim:

The ornamental design for a trailer body, as shown and described.
